[57] CLAIM

The ornamental design for a toy rocker, as shown and described.

DESCRIPTION

FIG. 1 is a side view of a toy rocker showing my new design, the opposite side view being the same as this side view;

FIG. 2 is a top view thereof;

FIG. 3 is a bottom view thereof;

FIG. 4 is a front view thereof;

FIG. 5 is a rear view thereof;

FIG. 6 is a sectional view thereof taken along lines 6—6 of FIG. 3; and,

FIG. 7 is a side view similar to that of FIG. 1 of an alternative embodiment thereof wherein the side has been marked to give the appearance of an automobile, the opposite side being marked the same as this side view and this embodiment having views which are the same as in FIGS. 2 to 6.
